UNITED STATES PATENT OFFICE.

WARREN D. CHASE, OF HARTFORD, CONNECTICUT.

TRACTION DEVICE.

Application filed July 9, 1920. Serial No. 395,024.

To all whom it may concern:

Be it known that I, WARREN D. CHASE, a citizen of the United States, residing at Hartford, in the county of Hartford and State of Connecticut, have invented certain new and useful Improvements in Traction Devices, of which the following is a specification.

This invention relates to anti-skidding or traction devices of the fixed point or anchored type and more especially to the anchoring devices by which the traction element is anchored in position.

It has for its objects to provide such a device which will not extend beyond the side edges of the widest radially outer peripherally extending part of the wheel, and so be protected by said part from injury by the curbing and the like; which will provide for the connection of the two terminal portions of the chain directly to each other to avoid pulling on the two separate plates as well as to avoid pulling on two parts in opposite directions axially of the plate fastening means and to avoid twisting or bending or breaking such plates or free ends thereof; to provide for such connection at a point between two adjacent spokes at such distance, peripherally of the wheel, from each spoke as will permit easy access from both sides of the wheel to promote the ease of applying the traction elements under the most trying weather and visual conditions; to provide a device which will be universally applicable to all wooden spoke wheels regardless of the size of spacing of said spokes; to provide a device in which the length of the traction element will not be governed or affected in any degree by the size of the spokes, but will be the same length for the same size tire in all cases; to provide a light self-contained independent unit which may be applied, removed and replaced without affecting the other units on the wheel, and which may be of cast metal and produced in large quantities at a small expense, all of which objects, among others, are accomplished by the construction, combination and arrangement of parts hereinafter more particularly set forth, described and claimed.

In the accompanying drawing, in which only the preferred form of my invention is illustrated:

Figure 1 represents a side elevation of a segment of a wheel with a device em-

bodying my invention applied thereto, the outer ends of the two adjacent spokes being spaced at approximately the usual average distance, the arrow indicating the direction of rotation of the wheel;

Figure 2, a similar view, the outer ends of the spokes being extremely close to each other, the traction element being omitted;

Figure 3, a similar view, the outer ends of the spokes being spaced extremely far apart, the traction element being omitted;

Figure 4, a plan view, looking from the hub radially outward, of the parts shown in, and as arranged in, Fig. 1, the cross-chain being, however, omitted;

Figure 5, a side elevation of outer plate 1;

Figure 6, a side elevation of inner plate 2; and

Figure 7, a sectional view on the line 7—7 of Fig. 3.

Figures 1, 2 and 3 give a good comparative illustration of the universal applicability of the device, showing it applied to the averagely spaced spokes and also to the two extremes.

Referring now in detail to the drawings, B designates the spokes, C the felly, D the rim, E the tire and F the traction element having its end links or terminal portions connected together by a connector G, which may be of any suitable construction, although the most satisfactory connector known to, and preferred by, me and indicated in the drawings is one made in accordance with the construction shown in the Reissue Patent No. 14,361 granted September 18th, 1917, on the invention of William H. McLaughlin.

The plates 1 and 2 are arranged respectively on the outside and inside lateral faces of two adjacent spokes B with portions of each of their inner faces in engagement with each of said spokes B, and their radially outer faces or edges in engagement with the inner peripheral face of the felly C.

Each of these plates is provided in the front portion, in the direction of rotation of the wheel, with a long slot 3 extending from near the front or forward end to a point beyond the medial portion of the plate, each slot being in length preferably approximately one half the length of each of said plates and being arcuate in form, following the form of said plates, which are arcuate in shape.

Each plate is also provided in its rear portion in the direction of rotation of the wheel with a short arcuate slot 4, which preferably also follows the arcuate shape of the plate.

In assembled relation on the wheel the slots 3 and slots 4 respectively of the two plates will register and bolts 5 and 6 will be passed through the respective pairs of slots 3 and 4, lock washers 7, of any usual type, will be slipped over their ends, and then nuts 8 will be screwed on the bolts to draw the two plates 1 and 2 into firm engagement with the lateral faces of the said two adjacent spokes, with their radial outer faces in engagement with the felly, as stated.

The plate securing bolts 5 and 6 should be so positioned in their slots as to engage their respective spokes, it being especially desirable that bolt 6 should be in engagement at all times with its respective adjacent spoke, while as to bolt 5 whether it actually engage its respective adjacent spoke or be positioned very close thereto, though not actually in engagement therewith is not of great importance, though it is important that it should be very closely adjacent said spoke in order to avoid leverage on a long free end, also, the point of anchoring or connection of the chain to the unit or in the unit will be between the two bolts so that there will be no free end or ends to be twisted, broken or damaged by a sudden and unusual pull or twist from the chain, but in case of such a pull it will be borne by the material of plate 1 between the two bolts 5 and 6, and transmitted by said bolts to plate 2. However, such a pull or strain will be decidedly unusual and very rare, though it might occur from a sudden turn at high speed or from the chain becoming considerably twisted.

To apply to a wheel with spokes spaced at the average distance, the bolt 6 will be positioned in the forward end portions of the slots 4 so as to provide a considerable length of the plates to extend along the sides of the adjacent spoke, with which the bolt 6 will always be in engagement in the arranged relation of the device on the wheel, and the bolt 5 will be located in the slots 3 at a short distance from the rear ends thereof, the two bolts 5 and 6 being between the two adjacent spokes in order to be as close together as possible while allowing room for the passage of the chain and in engagement with or, as to bolt 5, closely adjacent, their respective spokes to prevent the end portions of the plates 1 and 2 from bending.

Where the spokes have their outer ends extremely close together, as indicated in Figure 2, bolt 6 will be located as above mentioned, but bolt 5 will be shifted to the other side of its spoke B and into the forward portions of its slots 3, there not being suffi-

cient room for it in the spoke interval in which bolt 6 is located.

Where the spokes have their outer ends extremely distantly spaced, as shown in Figure 3, the bolt 5 will be moved back to its rearmost position in the slots 3 and the bolt 6 will be located in the same interval between the two adjacent spokes, the two bolts being located in their respective pairs of slots as near the respective ends of the plates 1 and 2 as possible while still retaining outside of the bolts a sufficient length of the plates to engage the lateral faces respectively of the two adjacent spokes sufficiently to get a good frictional grip, both bolts being preferably in engagement with their respective spokes.

The positions of the bolts 5 and 6 in their respective pairs of slots 3 and 4 will therefore be regulated by the intervals between the spokes of the wheel to which the particular unit is applied, having in mind that the bolts should be as near to their respective spokes as possible to guard against leverage, and for the same reason as close to each other as the above and superior considerations will permit.

Plate 1 is provided between the adjacent ends of slots 3 and 4 with a short preferably straight slot 9 so disposed that its radially outer end is located in advance, in the direction of rotation of the wheel, of its radially inner end, and its longitudinal central line is disposed at an angle of approximately forty-five degrees to a radial line.

The particular arrangement and location of this slot 9 is of importance, as will hereinafter appear.

The plate 1 is provided on each side radially outside of said slot 9 and adjacent to it and the edge of the plate with a reinforcing web 10 to make up for the material lacking in the area in said slot 9, the radially outer face of this web 10 being flush with the radially outer edge of the plate and bearing against the inner peripheral face of the felly.

The plate 2 is provided between the adjacent ends of its slots 3 and 4 with a large wide and deep recess 11 extending from the radially inner edge of said plate, and radially outside of said recess and on the inner side with an integral reinforcing web 12, the radially outer face of which is flush with the radially outer edge of plate 2 and bears against the inner peripheral face of the felly.

In the arranged relation of said plates 1 and 2 on the wheel the center of slot 9 and the center of recess 11 register with each other.

The recess 11 is of much importance as actual experience has demonstrated that to use a plate of this type and pass the chain over the radially inner edge thereof and then connect it to another plate such as plate

1, results in a pivotal point at the point of attachment with the latter plate and a swinging movement from said pivotal point of the chain against the radial inner edge 5 of the inner plate such as an unrecessed plate corresponding otherwise to my plate 2, and this when the chain is under severe stress in taking hold of the ground or road bed. This results in very quickly cutting 10 through the chain against the inner radial edge of the inner plate, this being accomplished sometimes more quickly than others, depending on road conditions, the load carried, the speed of travel, and the ability of 15 the operator to drive in such a way as to spare his machine. Also, in some makes of trucks the brake drum is of such size and so located that it would be impossible to get a chain through between it and the inner edge 20 of the inner peripheral face of the felly were an unrecessed inner plate employed.

To apply the chain, terminal link H is inserted from the inner side of the wheel into slot 9 so that its end projects laterally 25 beyond the outer lateral face of outer plate 1, the chain is then passed transversely around the tire, with a portion lying in recess 11, and the other terminal link I is slipped into connector G, which is then 30 hooked into the projecting end of terminal link H, after which the guard is closed and the operation is complete.

It will be noted that the bolt 6 is always 35 on the same side of its respective spoke and always close to the slot 9, and that in use the radially outer end of slot 9 is always in advance, in the direction of rotation of the wheel, of the radially inner end, with the result that as the traction element F takes 40 hold there is a tightening of the endless band, resulting in a radially outward pull, also a peripheral pull forcing the link H against the inclined rear wall of the slot 9, acting to force the plate 1 radially outward 45 and the bolt 6 peripherally of the wheel against its adjacent spoke, so that the radial and peripheral strains, as well as the very occasional lateral strains will be distributed 50 between the spokes and felly, and the usual lateral strains will be entirely borne or absorbed by the transverse endless traction element.

I have found from actual tests that with this 55 construction the actual strains upon the anchoring plates are so reduced and distributed and leverage eliminated to such an extent that plates of forged or other steel are not necessary and that malleable cast iron plates will more than meet all requirements, 60 that because of the peculiar arrangement the single size of plate will fit upon all sizes of wooden spoked wheels and will suffice for all sizes of trucks, and also, that as now designed, the plates when taken from the 65 molds may be immediately applied to the

wheels and used without need for any further operation or step of manufacture.

The preferred form is illustrated and described by way of example only as I recognize that various changes may be made and 70 do not wish at all to be understood as limiting myself to the construction illustrated, but on the contrary assert my right to protection on the invention defined by the appended claims broadly in all possible 75 embodiments.

Having thus described my invention, what I claim as new and desire to secure by Letters Patent is:

1. A device for anchoring traction elements to a spoked wheel, said device comprising a short segmental plate adapted to be held against the lateral faces of two adjacent spokes and in engagement with the inner peripheral face of the felly, and 80 means for holding said plate in such position, said plate having a slot through which a terminal portion of the traction element may be passed for direct connection to the other terminal portion thereof, the longitudinal central line of said slot extending 85 at an angle of approximately forty-five degrees to a radial line.

2. A device for anchoring traction elements to a spoked wheel, said device comprising a short plate adapted to be held against the lateral faces of two adjacent spokes and in engagement with the inner peripheral face of the felly, and means for holding said plate in such position, said 90 plate having a slot through which a portion of the traction element is to be passed, said means engaging a spoke immediately adjacent to said slot and on the same side and to the rear of said slot in the direction of rotation of said wheel, and said slot having its forward end, in the direction of rotation of said wheel, at a greater distance radially from the axis of the wheel than its rear end, so that the chain in pulling peripherally of 95 the wheel will have a tendency to ride up the inclined wall of said slot and so force the plate radially outwardly and said means peripherally against said spoke so that the radial and peripheral strains will be distributed 100 between said spoke and felly.

3. A device, for anchoring traction elements to spoked wheels, comprising two plates to engage opposite lateral faces of two adjacent spokes and the inner peripheral face of the felly, and provided with registering slots, the length of which is equal to substantially half the length of 110 said plates to permit of a wide range of adaptability to wheels with different spoke intervals, said slots extending from a point near one end of their respective plates toward the other end of said plate, said plates 115 also having registering perforations near their other ends, and being formed with 120 125 130

registering openings located between said perforations and the adjacent ends of said slots, said openings permitting the two terminal portions of the traction element to be directly connected to form an endless transversely arranged traction element anchored against peripheral movement as a whole, and bolts passing through said slots and perforations to draw said plates against

3 the opposite lateral faces of said two adjacent spokes.

4. A device, for anchoring a traction element to a spoked wheel, comprising two arcuate plates to engage opposite lateral faces of two adjacent spokes and the inner peripheral face of the felly and provided with arcuate registering slots, the length of which is equal to substantially half the length of said plates to permit of a wide range of adaptability to wheels with different spoke intervals, said slots extending from a point near the forward end, in the direction of rotation of said wheel, of said plates and having their peripherally extending walls parallel to the radially outer face of said plates, said plates further having short arcuate registering slots near their rear ends to increase said adaptability, the plate located on the inner lateral face of the wheel being provided with a wide and deep recess extending from its radially inner edge, said recess being located between the adjacent ends of the slots of said plate, and the plate located on the outer lateral face of said wheel being provided between the adjacent ends of its slots with a short straight slot to receive one end portion of said traction element, both ends of this latter slot being closed and its rear wall extending at an angle of approximately forty-five degrees to a radial line to have a wedging action, a bolt passing through said long slots, and a bolt passing through said short arcuate slots between said two adjacent spokes and in engagement with the rear spoke thereof, and means working on said bolts to draw said plates into engagement with said spokes.

5. A device, for anchoring a traction element to a spoked wheel, comprising two arcuate plates to engage opposite lateral faces of two adjacent spokes and the inner peripheral face of the felly and provided with arcuate registering slots, the length of

which is equal to substantially half the length of said plates to permit of a wide range of adaptability to wheels with different spoke intervals, said slots extending from a point near the forward end, in the direction of rotation of the wheel, of said plates, which are further provided, near their rear ends, with registering perforations and, between said perforations and the adjacent ends of said slots, with registering openings to receive a portion of the traction element, and have formed integral with them respectively, radially outside of said openings, laterally extending reinforcing webs, and bolts passing through said slots and perforations respectively to draw said plates together on said two adjacent intervening spokes.

6. In a device for anchoring a traction element to a spoked wheel, the combination of two plates to engage opposite lateral faces of two adjacent spokes and the inner peripheral face of the felly and provided with arcuate registering slots, the length of which is equal to substantially half the length of said plates, said plates having registering perforations, and formed with registering openings between said slots and perforations, the radially inner end of the opening in one of said plates being closed, the latter opening having one end disposed at a greater distance radially from the axis of the wheel than its other end to promote compactness in a peripheral direction, traction element extending through registering openings and comprising a flexible member having two terminal loops and a removable connector joining said terminal loops to form an endless transversely arranged traction element anchored against movement bodily peripherally of the wheel, and means passing through said slots and perforations respectively to hold said plates firmly in arranged relation on the wheel in engagement with said two adjacent spokes and the inner peripheral face of the felly.

In testimony whereof, I have signed my name to this specification in the presence of two subscribing witnesses.

WARREN D. CHASE.
